UNITED STATES PATENT OFFICE.

JOSEPH S. WITHERS, OF CHARLOTTE, NORTH CAROLINA.

FOUNTAIN-BRUSH.

SPECIFICATION forming part of Letters Patent No. 565,950, dated August 18, 1896.

Application filed March 23, 1896. Serial No. 584,502. (No model.)

To all whom it may concern:

Be it known that I, JOSEPH S. WITHERS, a citizen of the United States, residing at Charlotte, in the county of Mecklenburg and State of North Carolina, have invented a new and useful Fountain-Brush, of which the following is a specification.

This invention relates to fountain-brushes, the same being designed for use in marking 10 bales, boxes, and all kinds of packages, as well as in applying stove-polish, blacking, or shoe-polish, paints, whitewash, &c.

The object of the present invention is to provide, in connection with a distributing- 15 brush, a liquid-containing reservoir having communication with the bristles of the brush, and a novel form of gate or slide for regulating the flow of material to the brush, the whole being constructed so as to be separable 20 for the purpose of disassociating the several parts thereof for cleaning.

Other objects and advantages of the invention will appear in the course of the subjoined description.

25 The invention consists in an improved fountain-brush embodying certain novel features and details of construction and arrangement of parts, as hereinafter fully described, illustrated in the drawings, and finally incorporated in the claims hereto appended.

In the accompanying drawings, Figure 1 is a perspective view of a fountain-brush constructed in accordance with this invention. Fig. 2 is a longitudinal section through the 35 same. Fig. 3 is a reverse plan view of the reservoir with the brush removed. Fig. 4 is a plan view of the brush, showing the feed-openings in the back thereof. Fig. 5 is a detail perspective view of the gate or slide.

40 Similar numerals of reference designate corresponding parts in the several figures of the drawings.

Referring to the accompanying drawings, 1 designates a hollow body forming the reservoir of the improved fountain-brush, the said reservoir being provided with a nozzle 2, through which the liquid may be introduced, said nozzle being closed by a screw-cap 3 or in other convenient manner. This reservoir 45 is provided at one end with a handle 4 and has at its bottom edge a depending flange 5,

which is adapted to partially surround and within which is received the back 6 of the distributing-brush. The reservoir is provided with a bottom 7 and is further provided 55 with a false bottom 8, and between these two bottoms is arranged a gate or slide 9, formed, preferably, of metal and of a shape corresponding somewhat to the shape of the bottom of the reservoir. This gate or slide is 60 provided at one end with a strap extension 11, terminating in a finger-loop 12, in which the operator's finger may be inserted for reciprocating the slide, and the gate or slide is also faced upon one or both sides with felt 65 13 or other soft flexible packing material, whereby a close contact and joint is formed between the said gate or slide and the bottom and false bottom of the reservoir.

The bottom of the reservoir, the false bottom, the gate or slide, and the back 6 of the brush are all formed with alining openings 70 14, through which the material within the reservoir is fed to the bristles of the brush. However, as the gate or slide 9 may be reciprocated, its feed-openings may be moved out of alinement with the other feed-openings in the bottom of the reservoir and the back of the brush, thus cutting off the flow of material 75 to the brush, while the felt or packing upon each side of the gate serves to prevent any leakage.

15 indicates a bail-shaped clamp, which is pivotally connected at its ends to the depending flange 5 of the reservoir. This bail may 80 be rocked downward for allowing the brush to be removed, or it may be rocked upward, so as to bind against the back of the brush and clamp the same against displacement. The bail 15 is provided near its center with a 85 notch 16, whereby it is adapted to straddle the strap extension 11 of the gate or slide. The bail 15 thus forms a stop for limiting the outward movement or withdrawal of the gate or slide just as the feed-openings therein are 90 brought into alinement with the corresponding openings in the reservoir and brush.

By the construction described it will be seen that the flow of material to the brush may be easily regulated or cut off, that provision is made for guarding against any leakage of such material when the brush is not in

use, and that the brush and the gate or slide may be readily removed for the purpose of cleaning the same.

The device is adapted for all kinds of marking and stencil-work, and as different forms of brushes may be required for different classes of work it will be apparent that various changes in the form, proportion, and minor details of construction may be resorted to without departing from the spirit or sacrificing any of the advantages of this invention.

Having thus described the invention, what is claimed as new is—

1. The combination with a reservoir having a depending flange, of a distributing-brush arranged under the reservoir and in communication therewith and included within said flange, and a bail-shaped clamp having pivotal connection with the reservoir and adapted to be swung into engagement with the brush for locking the same to the reservoir, substantially as described.
2. The combination with a reservoir having

a depending flange for embracing the distributing-brush, of a distributing-brush removably fitted within said flange and having feed-openings which register with corresponding openings in the bottom of the reservoir, a gate or slide interposed between the reservoir and brush, the bail-shaped clamp having pivotal connection with the reservoir and adapted to embrace the back of the brush and lock the same in place, and a handle extension on the gate or slide operating through a notch in the bail-shaped clamp, whereby said clamp acts as a stop for the gate or slide, substantially in the manner and for the purpose specified.

In testimony that I claim the foregoing as my own I have hereto affixed my signature in the presence of two witnesses.

JOSEPH S. WITHERS.
